UNITED STATES PATENT OFFICE.

THOMAS LUND, OF BEVERLY, MASSACHUSETTS, ASSIGNOR TO UNITED SHOE MACHINERY COMPANY, OF PATERSON, NEW JERSEY, A CORPORATION OF NEW JERSEY.

PUNCHING-MACHINE.

1,161,059.

Specification of Letters Patent. Patented Nov. 23, 1915.

Application filed May 16, 1914. Serial No. 839,020.

To all whom it may concern:

Be it known that I, THOMAS LUND, a citizen of the United States, residing at Beverly, in the county of Essex and State of Massachusetts, have invented certain Improvements in Punching-Machines, of which the following description, in connection with the accompanying drawings, is a specification, like reference characters on the drawings indicating like parts in the several figures.

This invention relates to punching machines and is illustrated in connection with a machine of the type shown in United States patent to Knight No. 783,403 for punching or perforating the toe tip of a shoe. When, as in machines of this type, hollow punches are used it is necessary that provision be made for permitting the escape of the pieces of waste material which are forced into and through said punches. At the same time the supporting base upon which the punch plate holder rests must be substantially rigid so that no springing of the plate and holder will take place. If punch plates having the punches arranged in a single uniform pattern were always used, a correspondingly shaped passage through the supporting base would be sufficient; but the arrangement of the punches differs greatly with different plates so that the size of the passage in the supporting base necessary to take care of all arrangements would be sufficient to weaken said supporting base materially.

One feature of the present invention consists of a supporting base in the form of a grating the bars of which are comparatively thin at their tops. These bars are of a depth sufficient to afford the necessary strength, while at the same time the spaces between them permit the escape of the pieces of waste material which are forced through the hollow punches. This and other features of the invention, including certain details of construction and combinations of parts will be described in connection with an illustrative machine and pointed out in the appended claims.

Referring now to the accompanying drawings, Figure 1 is a perspective of one end of a punching machine in which the present invention is embodied, and Fig. 2 is a perspective of the grating which forms a support for the punch plate holder.

55 Rotatably mounted in the frame 1 of the

machine is a shaft 3 fast to which is a sleeve having formed thereon two eccentrics one of which is shown at 5, said shaft being driven from a loose pulley 7 through a clutch of any suitable type which may be thrown into operation by a downward pull upon the treadle rod 9. The eccentrics 5 are connected by means of rods 11 with a plunger 13 having a flat under surface. The punch plate holder 15, which is made in two parts fastened together in any suitable manner, carries a series of hollow punches 17 and a yielding stripper plate 19. In the operation of the machine a toe tip is placed on the stripper plate 19 with its inner edge against the yielding gage 20, and the treadle rod 9 is then depressed. The plunger 13 thereupon descends forcing the hollow punches 17 through the stock and moving the stripper plate 19 downwardly. The clutch is of the one revolution type, and when the plunger 13 rises and comes to rest in the position shown the yielding plate 19 has stripped the toe tip from the punches so that it may readily be removed.

The small disks of material which are removed by the hollow punches and are forced into and through said punches become tightly packed together during the operation of the machine, and these cylindrical accumulations are commonly known as "pills". After the punches have become filled with the punchings these "pills" are ejected from the lower ends of said punches as new punchings are produced. It is essential that provision be made for the escape of these pills since otherwise the punches are liable to be broken. If the same pattern or arrangement of punches were always used, this would be a simple matter, but the pattern of the punches, as well as the location of the pattern, with respect to the edge of the punch plate varies with different plates. The portion 21 of the base of the machine which supports the punch plate holder 22 is accordingly made in the form of a grating, the spaces between the bars being comparatively large so that with any given punch plate the pills will drop through the grating. In order, however, to provide for a case in which one or more cylindrical pills should be forced directly against the top of one or more of the grate bars, said grate bars are tapered at their upper portions; and the openings 23 in the

punch plate holder 22 are made of a diameter considerably greater than the diameter of the pills which are formed. The probability is very great that with a given pattern of punches no pills will strike squarely upon the narrow top of a grate bar but if such a condition does occur the cylindrical pill will be crumpled in the bore 23 so that the direction of its downward thrust will be changed and the pill will be forced between the grate bars. This grating thus furnishes a rigid support for the punch plate holder so as to prevent any possibility of the springing of said holder and at the same time permits the escape of the pieces of waste material. For convenience in the above description the hollow punches have been described as cylindrical but it should be understood that the shape of the punches is immaterial.

Although the invention has been set forth in connection with a particular machine, it should be understood that the invention is not limited in the scope of its application 25 to the particular machine shown and described.

Having thus described my invention, what I claim and desire to secure by Letters Patent of the United States is:

30 1. A machine of the class described having, in combination, a punch plate, hollow punches carried thereby, a holder for said plate, means for pressing against the punches pieces of material whereby pills of 35 waste material are forced down through

said punches, and a grating for supporting said holder and permitting the escape of said pills.

2. A machine of the class described having, in combination, a punch plate, hollow 40 punches carried thereby, a holder for said plate, means for pressing against the punches pieces of material whereby pills of waste material are forced through the punches, and a grating for supporting said 45 holder and permitting the escape of said pills, the bars of said grating being tapered at their upper portions and said holder being provided with a passageway of larger cross-section than that of said pills. 50

3. In a machine of the class described having hollow punches and a punch holder, a support for the punch holder comprising a grating the bars of which are tapered at their upper portions to permit the escape 55 of the waste material which is forced through the hollow punches.

4. In a machine of the class described having a punch holder, a support for the punch holder comprising a rigid grating 60 the upper portions of the bars of which are of small cross-section.

In testimony whereof I have signed my name to this specification in the presence of two subscribing witnesses.

THOMAS LUND.
